UNITED STATES PATENT OFFICE.

HUBERT K. KRANTZ, OF BROOKLYN, NEW YORK, ASSIGNOR TO WESTINGHOUSE ELECTRIC & MANUFACTURING COMPANY, A CORPORATION OF PENNSYLVANIA.

SWITCH-OPERATING MECHANISM.

Application filed December 21, 1920. Serial No. 432,339.

To all whom it may concern:

Be it known that I, HUBERT K. KRANTZ, a citizen of the United States, and a resident of Brooklyn, in the county of Kings and 5 State of New York, have invented a new and useful Improvement in Switch-Operating Mechanism, of which the following is a specification.

My invention relates to switch-operating 10 mechanism and particularly to operating mechanism for switches disposed in inaccessible places and actuated by remote operating mechanism.

One object of the invention is to provide 15 a switch-operating mechanism for switches that are mounted upon ceilings and other inaccessible places, whereby an operator may actuate a switch disposed at a remote point.

Another object of the invention is to provide 20 a switch-operating mechanism having the above characteristics wherein a single switch or a plurality of remotely spaced switches that are mounted upon a ceiling 25 may be actuated by a single operating handle or "shipper rod" that is accessible to an operator standing upon the floor.

Another object of the invention is to provide 30 a simple and inexpensive mechanical connection between an enclosed switch of standard construction and a shipper rod whereby the switch is operated in response to movement of the shipper rod and whereby independent movement of the switch is 35 permitted.

A further object of the invention is to provide 40 a simple apparatus for connecting the shipper rod to the electrical switch having a snap-action opening movement, whereby the switch may open with a snap action without interference with the actuating mechanism.

These and other objects, that will be made 45 apparent throughout the further description of the invention, are attained by means of the apparatus hereinafter described and illustrated in the accompanying drawings: wherein,

Figure 1 is a front plan view of a switch 50 box and the operating mechanism for the switch;

Fig. 2 is a side elevation of the apparatus shown in Fig. 1, showing the box and operating mechanism in side elevation:

Fig. 3 is a side elevation of a modified 55 form of switch-actuating mechanism:

Fig. 4 is a front plan view of the apparatus shown in Fig. 3:

Fig. 5 is a front plan view of a switch box and a modified form of switch-actuating 60 mechanism:

Fig. 6 is a side elevation of the apparatus shown in Fig. 5:

Fig. 7 is a side elevation of a modified 65 form of switch-operating mechanism:

Fig. 8 is a front elevation of the mechanism illustrated in Fig. 1:

Fig. 9 is a side elevation of a modified 70 form of switch-operating mechanism shown connected with a plurality of switch-operating shafts; and

Fig. 10 is a diagrammatic illustration 75 of switch-operating mechanism, wherein a rope, accessible to a plurality of operators, takes the place of the shipper rod.

Referring to the drawings, the apparatus includes a metallic switch box 11 for containing an electrical switch suitable for controlling lighting or motor circuits in factories and the like. The switch mechanism 80 usually employed in such installations consists of a pivoted blade member that is adapted to be moved into engagement with a contact jaw member for the purpose of establishing a circuit through a lighting system or a power motor. Such switches are provided with suitable actuating mechanism for imparting a snap action during the opening and closing movements thereof.

Switches of the above described type are severally provided with an operating shaft or lever 12 which extends exteriorly of the housing and which may be manually operated to open and to closed position.

An object of the invention is to provide suitable mechanism whereby the switch may be actuated to open and to closed position by means of a shipper rod.

As illustrated in Figs. 1 and 2, the housing 100 11 is supported upon a ceiling structure 13, to which is secured, at a point adjacent

the housing 11, the shipper-rod bracket 14 which consists of a socket member 15 in which the upper end of a shipper rod 16 is pivoted for rotation about a bolt 17.

5 The switch-actuating mechanism includes a rocking lever 18 having two arms 19 and 21 disposed, with respect to each other, at an angle of substantially 90° or more. The rocking lever is mounted for limited rotary 10 movement upon the operating shaft 22 of the switch mechanism, and the extreme ends of the levers 19 and 21 are provided with outwardly extending projections 23 and 24, respectively, which separately engage the 15 operating handle 12, which, in the instance illustrated, is an integral part of the switch shaft 22.

It will be seen from the foregoing that, when the operating lever 18 is rotated in a 20 counter-clockwise direction, the handle 12 is moved from the closed position illustrated to an open position wherein the handle will occupy a position substantially 90° from that shown in Fig. 2, as illustrated in broken 25 lines. By reason of the space provided between the contact extensions 23 and 24, the rocking lever 18 does not interfere with the snap-action movement of the operating handle 12.

30 In the construction illustrated in Figs. 1 and 2, the operating lever 18 is provided with a gear 25 that is secured thereto and is adapted to impart rotary movement to the operating lever 18. The gear 25 is actuated 35 by means of a gear sector 26 that is pivoted upon the housing 11 by means of a shaft 27. The teeth of the sector 26 are meshed with those of the gear 25 to cause rotary movement of the gear when the sector is 40 oscillated.

A helical spring 25', having one end secured to the housing, as at 29, and the other end secured to a pin 30 on the sector 26, serves to normally yieldingly retain the sector 26 in a predetermined position, as illustrated in Fig. 2.

The shipper rod 16, which is of sufficient length to extend within reach of an operator standing upon the floor, is flexibly 50 connected to the sector 26 by means of a link 32 which is pivoted, at one end, to the shipper rod by means of a bolt 33 and, at the other end of the sector, by means of a shaft 34.

55 A pulley 20 is secured to the sector 26 for receiving a belt which may extend to a similar pulley on a remotely disposed switch mechanism. In this manner, a plurality of switches may be operated by a single shipper rod. This feature of the invention will be hereinafter more fully described in connection with apparatus illustrated in Figs. 7, 8 and 9.

60 The operation of the apparatus is as follows: Assuming the switch to be in the

neutral position illustrated in Figs. 1 and 2, the switch is moved to open position by movement of the shipper rod 16 to the left or in a clockwise direction. This movement imparts a rotary movement to the sector 26 in a clockwise direction, thus causing the gear 25 to be turned in the opposite direction. Counter-clockwise movement of the operating lever 18 causes the extension 23 to engage the operating handle 12 and move 75 it to open position wherein it occupies a position indicated in broken lines in Fig. 2. Upon the release of the shipper rod handle, the spring 25' returns the sector 26 to the neutral position illustrated in full lines in 80 Fig. 2.

To close the switch, the shipper rod is moved to the right, thus imparting clockwise movement to the gear 25 and the operating lever 18. The extension 24 engages 85 the operating handle 12 and causes it to return to its original closed position.

Referring to Figs. 3 and 4, a modified form of switch-actuating mechanism is illustrated, wherein actuating mechanism is 90 mounted upon a bracket 35 that is secured to the ceiling 36 to pivotally support a shipper rod 37 by means of a pivot shaft 38.

In this construction, the switch shaft 39 is actuated by means of an operating lever 95 41 having a pair of oppositely disposed levers 42 and 43 that are provided at their extreme ends, with inwardly projecting extensions 44 and 45, respectively. The rocking lever 41 is adapted to be rotated through 100 substantially 180° between engagements of the extensions 44 and 45 with opposite sides of the operating handle 46 that is an integral part of the switch shaft 39. A gear 47 is secured to the rocking lever 41 and serves 105 to turn the said lever.

An internal gear sector 48 is pivoted to the bracket 35 upon a shaft 49, and the shipper rod 37 is pivotally connected thereto by means of a bolt 51 which operates in a 110 slot 52 provided in the shipper rod 37.

The sector is normally yieldingly retained in the predetermined position illustrated in Fig. 3 by means of a spring 53 that is wound around the shaft 49. The ends 54 and 55 of the spring 53 are disposed on opposite sides of a pin 56 that is secured to the bracket 35. 115

The sector 48 is provided with a pin 57 that extends between the ends 54 and 55 of the spring and serves to displace the 120 end 55 when the sector is turned in a counter-clockwise direction and to displace the end 54 when turned in a clockwise direction. It will be apparent, therefore, that the sector 48 will be returned to the neutral position 125 illustrated when the shipper-rod handle 37 is released.

The operation of this apparatus is somewhat similar to the operation of the apparatus illustrated in Figs. 1 and 2. The 130

rocking movement of the sector 48 imparts rotary movement of the gear 47 to the shaft 39. The extensions 44 and 45 serve to operate the handle 46 to open and to closed positions, respectively, in a manner somewhat similar to the operation of the switch mechanism previously described.

Referring to Figs. 5 and 6, another modified form of apparatus is illustrated. The 10 switch-operating mechanism is mounted upon a bracket 58 that is secured to the ceiling and serves to support the switch box 59. A shipper rod 61 is pivoted to the bracket by means of a bolt 62.

15 The switch shaft 63 is actuated by a rocking lever 64 which is similar to the rocking lever 18 of the apparatus illustrated in Figs. 1 and 2, in that the operating lever arms 65 and 66 are disposed at an angle of 20 substantially 90°.

The rocking lever 64 is secured to a shaft 66 that is mounted for rotation on the bracket 58. A drum 67 is secured to the shaft 66 and is rotated by means of a cable 68 which is wound several times around the drum and has its ends secured to opposite ends of a rocking beam 69 that is pivoted to the bracket 58 upon a shaft 71.

25 The rocking beam 69 is normally yieldingly retained in the predetermined position illustrated in Figs. 5 and 6 by means of a helical spring 72 that is wound around the shaft 71. The ends 73 and 74 of the spring 72 are disposed on opposite sides of 30 a pin 75 that is secured to the frame 58.

35 A pin 76, carried by the rocking beam 69, projects between the ends 73 and 74 of the spring and serves to displace the end 73 when the rocking beam 69 is turned in 40 a counter-clockwise direction and to displace the end 74 when the rocking beam is moved in a clockwise direction. It will be seen from the foregoing that the rocking beam 69 will be turned by the spring 72 to 45 its original position when the shipper rod is released by the operator.

The shipper rod 61 is operatively connected to the rocking beam 69 by means of a pin 77 carried by the rocking beam 69 50 which projects through a slot 78 provided in the shipper rod.

55 The operation of the apparatus is as follows: Assuming the parts of the apparatus to be in the position illustrated in Figs. 5 and 6 wherein the switch is in closed position, the switch will be opened by movement of the shipper rod to the right. This movement of the rod causes counter-clockwise rotation of the rocking beam 69 which, 60 in turn, imparts a rotary movement, in the same direction, to the rocking lever 64 by reason of the cable 68 which is wound around the drum 67.

After the rocking lever 64 is moved a

predetermined distance, the switch will snap 65 to open position wherein the operating handle 70 will occupy a position at an angle which is substantially 90° from its original position. When the handle is released by the operator, the spring 72 will return the 70 rocking beam 69 to its original position.

In order to close the switch, the shipper rod is moved to the left, thereby causing reverse movement of the rocking lever 64 and consequent closing movement of the 75 switch.

80 It will be understood that the switch-operating handle 70 is separately engaged by projections 79 and 81 that are carried on the extreme ends of the levers 65 and 66, respectively. When the shipper rod is released by the operator, the spring 72 will again return the rocking lever 69 to its original position.

85 Referring to Figs. 7 and 8, another modified form of apparatus is illustrated wherein the switch-operating mechanism is supported upon a bracket 82 that is secured to the ceiling. In this construction, the shipper rod 83 is pivoted to the bracket by means 90 of a shaft 84 at a point intermediate the extreme upper end of the shipper rod and the lower end thereof. The upper end of the shipper rod is forked, having two prongs 85 and 86 that straddle the axis of the 95 switch-operating handle or shaft 87 that projects from the switch housing 88.

100 A pulley 89, that is provided with oppositely disposed pins 91 and 92, is mounted for rotation upon a shaft 93 that is secured to the bracket 82 in axial alignment with the axis of the switch-operating shaft. The pulley is provided with a drum portion 94 around which a cable 95 is wound several turns. The ends of the cable are secured 105 to the extreme ends of the prongs 85 and 86, as at 96 and 97, respectively.

110 It will be seen from the foregoing that, when the shipper rod 83 is oscillated, rotary movement will be imparted to the pulley 89 by reason of the frictional engagement of the cable 95 with the drum 94. The pins 91 and 92 that are carried by the pulley 89 separately engage opposite sides 115 of the switch handle 87 and move it to closed and open positions, respectively, in the manner described in connection with the apparatus illustrated in Figs. 3 and 4.

120 As in the construction illustrated in Figs. 1 and 2, the drum 94 is provided with the pulley 89 for the purpose of actuating a remotely disposed switch.

125 Referring to Fig. 9, the apparatus is shown connected with a plurality of switch handles 87 that are operated by means of the pulleys 89, one of which is connected to the shipper rod 83 in the manner just described while the other is operated by means

of a belt 98 connecting the pulleys. The pulleys are normally yieldingly retained in the predetermined position illustrated in Fig. 9 by means of a pair of springs 99 that may be secured to any stationary part of the building structure.

It will be apparent from the foregoing that, when the shipper rod 83 is moved, rotary movement will be imparted to both of the pulleys and when the shipper rod 83 is released, the springs 99 will return the pulleys to their original position. It will also be apparent that pulleys may be supplied to the apparatus disclosed in Figs. 3, 4, 5 and 6 for the purpose of operating a plurality of switches by one shipper rod.

In Fig. 10, I have illustrated an application of the invention similar to that disclosed in Fig. 9, except that the cable 100 serves as a shipper rod. In the construction illustrated in Fig. 10, the endless cable 100 is mounted on an idle pulley 101 and a switch-actuating pulley 102 which is provided with pins 103 for alternately engaging the switch handle 104. The cable is adapted to extend past a plurality of machines operated by the motor controlled by the switch and is accessible to, and operable by, an operator of any one of the machines. Springs 105 are provided to return the pulley 102 to its neutral position.

The apparatus above described is simple and inexpensive to manufacture and all parts thereof are accessible for inspection and repair. The construction is such that the switch may be manually actuated by the operator independently of the shipper-rod mechanism or the switch may be actuated by an over load release device. It is, therefore, unnecessary to disconnect the operating mechanism in order to inspect the switch and to actuate the switch during the inspection.

While I have described and illustrated but four embodiments of my invention, it will be apparent to those skilled in the art that various changes, modifications, substitutions, additions and omissions may be made in the apparatus illustrated without departing from the spirit and scope of the invention, as set forth in the appended claims.

I claim as my invention:

1. Mechanism for operating a switch having an operating shaft, a lever having a lost-motion connection therewith, and an operating member for actuating the said lever and normally yieldingly retained in a neutral position permitting independent movement of the said shaft to operative and inoperative positions.

2. Mechanism for operating a switch having an operating shaft, a lever pivoted on the said shaft and having a lost-motion

connection therewith and an operating member for actuating the said lever and normally yieldingly retained in a neutral position permitting independent movement of the said shaft to operative and inoperative positions.

3. Mechanism for operating a switch having an operating shaft, a lever having a lost-motion connection therewith, for permitting independent movement of the switch between operative and inoperative positions, an operating member for actuating the said lever, and means for normally yieldingly retaining the said lever in a predetermined position.

4. Mechanism for operating a switch comprising an operating member, means actuated thereby for operating the switch permitting independent movement of the switch to operative and inoperative positions, and means for normally yieldingly retaining the said means in a predetermined position.

5. The combination with a switch and an operating shaft, a member rotatably mounted on the shaft for operating the shaft and having a lost-motion connection thereto for permitting movement of the switch to open or closed position independently of the said member and a shipper rod having driving connection to the said member for operating the said switch.

6. The combination with a switch-operating shaft, a gear having limited rotary movement thereon, an operating member, a gear member connected thereto for imparting rotary movement to the gear and means for returning the operative member to a predetermined position permitting independent movement of the switch-operating shaft.

7. The combination with a switch-operating shaft, a rotatable member substantially axially aligned with the shaft and having a lost-motion connection therewith, an operating member, means connected thereto for imparting rotary movement to the said member and means for returning the operating member to a predetermined neutral position permitting independent movement of the switch-operating shaft.

8. The combination with a switch mounted upon a support and having an operating shaft, of a shipper rod carried by the support and having an operative lost-motion connection to the said shaft for permitting independent movement of the switch-operating shaft to operative and inoperative positions.

9. The combination with a switch mounted upon a support and having an operating shaft, of a shipper rod carried by the support and having an operative lost-motion connection to the said shaft for permitting independent movement of the switch-operating

erating shaft to operative and inoperative positions and means for returning the shipper rod to a predetermined neutral position.

10. The combination with a plurality of 5 switches mounted upon a support and each having an operating shaft, of a shipper rod carried by the support and having an operative lost-motion connection to the said

shafts for permitting independent movement of the shafts with respect to one another and to the shipper rod. 10

In testimony whereof, I have hereunto subscribed my name this eleventh day of December 1920.

HUBERT K. KRANTZ.
